JOHN F. O'CONNOR, OF CHICAGO, ILLINOIS, ASSIGNOR, BY MESNE ASSIGNMENTS, TO
W. H. MINER, INC., A CORPORATION OF DELAWARE.

SIDE BEARING FOR RAILWAY CARS.

Application filed April 3, 1924. Serial No. 703,900.

This invention relates to improvements in side bearings for railway cars.

One object of this invention is to provide a side bearing especially adapted for use on railway cars and wherein the parts are so arranged that the anti-friction elements proper will return to normal position under the influence of gravity when the load is released.

Another object of my invention is to provide an anti-friction bearing especially adapted for railway side bearings, so designed that a plurality of anti-friction elements are employed which are automatically returned to their normal position after being actuated, this returning movement being solely under the influence of gravity and without the aid of extraneous devices, to the end that the anti-friction bearing is always in condition to operate for its full intended movement.

More specifically, an object of the invention is to provide an anti-friction bearing employing at least two rocking anti-friction elements, each of which is normally positioned at one extreme end of its path of movement, said elements being oppositely disposed so that one element will always be available for operation regardless of the direction in which the side bearing is actuated, and whereby said elements may be made automatically self-returning under the influence of gravity without the aid of springs or the like. By arranging the anti-friction elements in alignment longitudinally of the bearing surface, I am enabled to use elements having a relatively wide bearing surface so that there will be no likelihood of crushing or otherwise injuring the elements under load.

Other objects and advantages of my invention will more clearly appear from the description and claims hereinafter following.

In the drawing forming a part of this specification, Figure 1 is a vertical sectional view taken through the ends of the body and truck bolsters of a railway car, showing my improvements in connection therewith. Figure 2 is a top plan view of the side bearing. And Figure 3 is a vertical sectional view taken substantially on the line 3—3 of Figure 1.

In said drawing, 10 denotes the upper side of a truck bolster of a railway car and 11 the under portion of the body bolster opposed thereto.

Referring to the drawing, the improved side bearing is shown as applied to the truck bolster and comprises, broadly, a base casting, housing or retaining member A; a pair of anti-friction elements or rockers B—B; 60 and a bearing plate C.

The housing A is more or less box-like in form, comprising vertical end walls 12 and vertical side walls 13 having laterally offset recessed portions 14 therein. A wear member or bearing plate C is adapted to be interposed between the housing and the truck bolster, said bearing plate extending beyond the housing as at 15, and said housing and wear member being connected by rivets 16 65 70 as shown. Rivets 17 may be used for securing the bearing plate C to the truck bolster. The side walls 13 of the housing may be provided with openings 18 therethrough at their lower ends for the removal of dirt, cinders or other foreign matter. The top and bottom of the housing are open and the anti-friction rocker elements B are arranged in longitudinal alignment therein so as to rock toward one another and project through the 80 open top of the housing.

These elements B, which are of like size and shape, are arranged in alignment longitudinally of the housing, each having trunnions 24 projecting outwardly from both 85 sides of the elements and adapted to extend in the recesses 14 to prevent the elements from being lifted outwardly through the top of the housing. Each element B has mutually divergent end faces 19 and 20, the latter face 90 having a large recess or cutout 21 therein. The bottom bearing face of each element is rounded or made arcuate toward one end, as indicated at 22 and the remainder of said bottom face is flat and tangential to this 95 curved portion so as to normally lie flat on the bearing plate C, as indicated at 23. The top of each element is provided with two flat faces 25 and 26, the former substantially parallel to the flat portion 23 of the bottom bearing face of the element, so that when the elements are in their normal position at the opposite ends of the housing, the end walls 19 will lie against the vertical end walls 12 of the housing, and the flat faces 23 and 25 100 105 will be horizontal, in which position the upper flat faces 25 may receive any pounding from the opposed body bolster, without causing injury to the rockers or to the bearing plate. The end faces 20 are inclined so that 110

they mutually diverge as they extend upwardly from the bearing plate, the lower ends of said faces being closely adjacent one another when the rockers are in their normal 5 unloaded position. Thus there will be substantially no shifting of the rockers longitudinally of the bearing plate and the rockers will always be in position for full travel.

On approaching movement of the bolsters, 10 the engagement of the rocker element by both the upper and the lower bearing plates will cause an actuation of one of the elements in one direction and upon removal of the pressure, said actuated rocker will return, 15 through gravity, to normal position.

The operation of the bearing is as follows, 20 assuming that the loaded bolster 11 is moved to the right relatively of the bolster 10. The anti-friction elements, being in their normal position at their opposite ends of the housing and lying against the vertical end walls thereof, the bolster 11 will engage the horizontal tops 25 of both the elements, but inasmuch as one of them is necessarily at its limit of movement 25 in the direction in which the bolster 11 is moving, that element will remain stationary while the other element is free to rock about its arcuate bearing face 22, relatively toward the stationary element and will therefore 30 take the load, rocking or tilting until the end face 20 abuts against the corresponding opposed face 20 of the adjacent element, at which time the flat face 26 of the element that has been actuated is at a level above the 35 top of the stationary element and is horizontal so that it takes the load over its full bearing area and permits the bolster 11 to slide thereon. As soon as the load is released, the roller which has been actuated or rocked, 40 will automatically return under the influence of gravity to its normal position, resting against the end of the housing. As the loaded bolster is moved in the reverse direction to that just described, that element B which 45 formerly moved will remain fixed while the other element which formerly remained stationary will take the load and rock toward the stationary element.

Thus it is seen that the elements will normally 50 be retained at the opposite end of the housing and when the body bolster moves in one direction under load, only one of the rocker elements will take the load to the end of its travel.

As hereinbefore pointed out, it will be noted that at the end of rocking movement, the actuated element will be in such a position that its end face is in close proximity to or abuts against the opposed end face of the 60 cooperating element and a flat portion of its upper bearing face will be substantially parallel to and engaged by the upper bolster, and should the length of the relative movement of the bolster be sufficient to bring the 65 rocker element to its extreme position, then

upon further movement in the same direction, the upper bolster may slide upon the flat face 26.

I have herein shown and described what I now consider the preferred manner of carrying out my invention but the same is merely illustrative and I contemplate all changes and modifications that come within the scope of the claims appended hereto.

I claim:

1. In an anti-friction bearing, the combination with a retainer provided with a continuous bearing surface and end walls; of a plurality of self-centering rocking members each provided with opposite bearing faces, the faces of said rocking members adjacent said bearing surface being disposed in engagement therewith, said rocking members being constructed to permit relative movement of the rocking members, said end walls serving to limit movement of said rockers in a direction away from each other, the bearing faces of said rocking elements in engagement with said bearing surface being curved in opposite directions and so constructed whereby movement of one of said rocking elements toward another effects projection of the bearing face of the element remote from the bearing surface beyond the remote bearing face of the adjacent element.

2. In an anti-friction bearing for railway cars, the combination with a retaining member adapted to be secured to a truck bolster and having a horizontal bearing surface therein; of a pair of rockers arranged at opposite ends in said retaining member, only one of said rockers taking the load and moving toward the other when the bearing is actuated, said rockers having a lower bearing surface adapted to rock on the bearing surface of the housing and having a flat upper bearing portion adapted to be parallel to the body bolster bearing surface and engageable thereby, when the rocker is actuated to its extreme position.

3. In an anti-friction bearing for railway cars, the combination with a housing adapted to be secured to a bolster or the like; of a pair of rockers normally arranged at opposite ends of said housing and adapted to rock on said bearing surface of the housing, only one of said rockers at a time taking the load and moving relatively of the other when the bearing is actuated, each of said rockers having a flat portion adapted to be parallel to the cooperating bolster when the rocker is at its normal position and also having a flat portion adapted to be parallel to said cooperating bolster when the rocker is rocked to extreme position.

4. In an anti-friction bearing, the combination with a housing having a horizontal bearing surface therein; of a pair of rockers arranged in alignment longitudinally of said bearing surface, said rockers when in normal

position each having an end wall abutting an end wall of said housing, the opposite ends of the rockers spaced closely to one another adjacent the housing bearing surface and inclined outwardly of said housing bearing surface, whereby one of said rockers may be rocked until its inclined end face abuts the opposed inclined end face of the other rocker.

5. In an anti-friction bearing for railway cars, the combination with a housing adapted to be secured on a bolster or the like and having an interior bearing surface; of a pair of self-returning rockers arranged at opposite ends of said housing and adapted to rock on said bearing surface, each of said rockers having a rounded bearing surface engageable on said bearing surface of the housing, and also having a portion of its outer bearing surface normally parallel to the bearing surface 10 of the cooperating opposed bolster and having another portion of the outer bearing surface adapted to be parallel to the opposed bearing surface of the last-mentioned bolster when the rocker is at the end of its rocking movement.

6. In an anti-friction bearing for railway cars, the combination with a housing adapted to be secured to a truck bolster and having a horizontal bearing surface therein; of a pair 15 of self-returning rockers arranged at opposite ends of said housing, only one of said rockers taking the load and moving relative toward the other rocker when the bearing is actuated, each of said rockers having a flat portion of its lower bearing surface normally bearing on said horizontal bearing surface,

and having the other portion rounded toward one end, each rocker also having a pair of flat portions on its upper side, one of said last-mentioned upper portions being horizontal when the rocker is in its normal position and the other being horizontal when the rocker is moved to the limit of its rocking movement.

7. In an anti-friction bearing of the character described, comprising a retainer adapted to be supported upon a bolster and provided with side and end walls, and a bearing plate; of a plurality of rockers mounted on said bearing plate, said rockers being weighted to maintain the same in predetermined position, and having opposite bearing faces, one set of which is disposed in engagement with said bearing surface, while the remaining bearing faces project outwardly beyond the free extremities of the walls of said retainers, said rocking members being formed to permit relative movement one toward the other, and to effect projection of the remote bearing face of one of said members, beyond the other during movement toward each other, the end walls of said retainer serving to limit movement of said rockers in a direction away from each other, whereby independent movement of one of said members with respect to the other is effected, depending upon the direction of movement of the bolster with which the remote bearing faces are engaged.

In witness that I claim the foregoing I have hereunto subscribed my name this 1st day of April, 1924.

JOHN F. O'CONNOR.
